(57) **CLAIM**

The ornamental design for tracks for amusement rides, as shown and described.

DESCRIPTION

FIG. 1 is a front perspective view of our new design for tracks for amusement rides.

FIG. 2 is a front side elevation view of FIG. 1.

FIG. 3 a back side elevation view of FIG. 1.

FIG. 4 is a right side elevation view of FIG. 1.

FIG. 5 is a left side elevation view of FIG. 1.

FIG. 6 is top plan view of FIG. 1.

FIG. 7 is a front perspective view of a second embodiment of our new design for tracks for amusement rides.

FIG. 8 is a front side elevation view of FIG. 7.

FIG. 9 a back side elevation view of FIG. 7.

FIG. 10 is a right side elevation view of FIG. 7.

FIG. 11 is a left side elevation view of FIG. 7; and,

FIG. 12 is top plan view of FIG. 7.

The support feet, support guy wires and the rider carriages are shown in dotted lines, which is for illustrative purposes only and is not part of the claimed design.

1 Claim, 12 Drawing Sheets
